(57) **CLAIM**

The ornamental design for a plunger adapter, as shown and described.

DESCRIPTION

FIG. 1 is a side perspective view of a plunger adapter
FIG. 2 is a front side elevational view of the plunger adapter of FIG. 1;
FIG. 3 is a rear side elevational view of the plunger adapter of FIG. 1;
FIG. 4 is a top plan view of the plunger adapter of FIG. 1; and,
FIG. 5 is a bottom plan view of the plunger adapter of FIG. 1.
The broken lines are included for the purpose of illustrating portions of the plunger adapter that form no part of the claimed design.
